UNITED STATES PATENT OFFICE.

JOHN VALIQUETTE AND MICHAEL VALIQUETTE, OF CUMMING'S BRIDGE, ONTARIO, CANADA.

LIQUID-AGITATOR.

No. 890,315.

Specification of Letters Patent.

Patented June 9, 1908.

Application filed September 28, 1907. Serial No. 394,999.

To all whom it may concern:

Be it known that we, JOHN VALIQUETTE and MICHAEL VALIQUETTE, both of the village of Cumming's Bridge, in the county of 5 Carleton, Province of Ontario, Dominion of Canada, have invented certain new and useful Improvements in Liquid - Agitators, of which the following is a specification.

Our invention relates to improvements in 10 liquid agitators and the objects of our invention are to provide an agitator, particularly adaptable for circulating the liquid and lime in the tanning process, whereby the labor hitherto necessary to accomplish this matter 15 is saved and the process is carried out with a decreased amount of lime; and it consists essentially of a vat having means thereon for vertically suspending the hides, a continuous chain provided with paddles extending 20 along the ends and bottom of the vat, and partitions preventing the hides from contacting with the chain, all as hereinafter more fully set forth and described in the accompanying specification and drawings.

25 In the drawings, Figure 1 is a sectional view through the agitator. Fig. 2 is a top view of the same. Fig. 3 is a perspective view of the agitator chain. Fig. 4 is a perspective detail showing the mode of suspension of the hides.

In the drawings like letters of reference indicate corresponding parts in each figure. A is the vat of the usual construction set on a suitable foundation B. Along the two 35 sides of the vat, piping a and b run being connected at the extremities to the side of the vat. The hides c are suspended vertically from this piping by means of hooks d connected to the hides and extending over 40 the piping.

C and D are two endless chains supported on two sets of sprocket wheels e, f, g, h, and i, which are supported on shafts j, k, l, m and n. The lower shafts m and n are journaled in 45 the sides of the vat and the upper shafts j, k and l are journaled in suitable bearings supported on standards, o, p and q, which are secured in the foundation B. The outer shaft l has a pulley r connected thereto, by 50 means of which the two chains may be rotated and the shaft j has a suitable form of tightening device s connected thereto.

Connected to both chains and extending substantially normal thereto, are a plurality 55 of paddles t which operate to stir the liquid or mixture of liquid and solid in the vat.

These paddles and the chain itself may be of any desired construction. The connecting means between the two, which I have illustrated in the accompanying drawing, comprises outwardly projecting lugs u, integral 60 with the chain and which are bolted to the paddles.

To prevent the hides swinging laterally and striking against the chain, we provide 65 partitions E and F, extending across the vats and reaching to the bottom of the hides. There are also provided guard bars G at the bottom preventing the hides touching the chain as it runs along the bottom, should 70 they become disengaged and drop down.

It will thus be seen that we have devised an exceedingly cheap and simple form of 75 agitator, which may be used for a variety of purposes. In operation, the chain is rotated continuously, insuring a complete circulation 80 of the liquid. Particularly is it adaptable for the purpose of circulating the liquid and lime in the tanning process, as in this case, the hides being hung vertically are reached 85 on all sides by the liquid which is in constant circulation. This is a considerable advance over the old method of treating with lime in which the hides were simply piled in a vat and the mixture of lime and liquid poured thereon.

While the invention has been described herein with great particularity of detail, yet it will be readily understood that in carrying out the construction of the same, changes 90 may be made therein without departing materially from the spirit of the invention.

What we claim as our invention is:—

1. An improved agitator for mixtures employed to treat solid substances, comprising 95 a plurality of chains extending into the mixture, paddles thereon, and means for preventing the solid substances contacting with the chain, as and for the purpose specified.

2. An improved agitator for the liquid employed to treat hides comprising a suitable vat, a chain running along the ends and bottom of the vat, means for supporting and rotating the same, paddles on the chains, and partitions at each end preventing the hides 100 contacting with the chains, as and for the purpose specified.

3. An improved agitator for treating hides comprising a suitable vat, means on the side thereof for suspending the hides vertically in 110 the vat, chains extending along the end and bottom of the vat, means for supporting and

rotating the same, paddles on the chains and partitions preventing the hides contacting with the chains, as and for the purpose specified.

5 4. An improved agitator for tanning processes, comprising a suitable vat, bars extending along the side of the same, to which the hooks on the hides are adapted to be connected, chains extending along the ends and 10 bottom of the vat, means for supporting and rotating the chains, paddles on the chains,

and partitions preventing the hides contacting with the chains, as and for the purpose specified.

Signed at Ottawa, Province of Ontario, ¹⁵
this 23rd day of September, 1907.

JOHN VALIQUETTE.
MICHAEL VALIQUETTE.
